UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

NEEDLE AND AWL MECHANISM OF CURVED-NEEDLE SEWING-MACHINES.

1,182,581.

Specification of Letters Patent.

Patented May 9, 1916.

Application filed September 12, 1910. Serial No. 581,636.

To all whom it may concern:

Be it known that I, FRANK W. MERRICK, a citizen of the United States, residing at Boston, in the county of Suffolk, State of Massachusetts, have invented a certain new and useful Improvement in Needle and Awl Mechanism of Curved-Needle Sewing-Machines, of which the following is a specification, reference being had therein to the accompanying drawings.

The invention relates to the needle and awl carriers of curved needle sewing machines, their supports and bearings, and the actuating connections thereof.

An embodiment of the various features of the invention is shown in the drawings, in which—

Figure 1 shows in side elevation, with the driving shaft in section, certain of the parts of a curved needle sewing machine, including the said embodiment. Fig. 2, Sheet 2, is a view showing mainly the awl-carrier and needle-carrier and the actuating connections thereof, with the parts in positions different from those occupied in Fig. 1. Fig. 3, Sheet 1, is a view showing separately the awl-carrier and needle-carrier and their supports, with the stands in vertical section. Fig. 4, Sheet 1, is a view of the parts that are shown in Fig. 3, but representing them in horizontal section and on a larger scale than in the preceding figures.

Having reference to the drawings,—the principal framework of a curved needle sewing machine is shown at 1, Fig. 1, and at 2 is represented the main shaft of the said machine, the said shaft being mounted in suitable bearings in connection with the said framework. The work-support of the machine is shown at 3, Figs. 1 and 2, and 4 is the presser between which and the said work-support the material to be operated upon is placed. Only a portion of the presser is shown.

A curved needle is shown at 5, a segmental needle-carrier at 6, a curved awl at 7, and a segmental awl-carrier at 8. The needle-carrier is shown furnished with a split needle-clamp, the loose member 6^a of which, Fig. 3, is provided with a screw-threaded stem 6^b that passes through a hole in the body of the needle-carrier and receives at the opposite side of the latter a nut 6^c, by turning which the clamp may be tightened upon the needle-shank, to secure

the needle, or loosened to permit the needle to be adjusted or removed. The awl-carrier is shown furnished with a similarly-constituted awl-clamp, the latter including a loose member 7^a provided with a screw-threaded stem 7^b that passes through a hole in the body of the awl-carrier, the said stem receiving at the opposite side of the said body a tightening nut 7^c. The needle-carrying portion of the segment 6 is slightly offset laterally, as shown best in Fig. 3, to enable the needle to be brought into line with the awl.

The features of the supports and bearings of the carriers are as follows: A supporting-stud 9 is mounted in small fixed stands or cheek-pieces 10, 11, at the front of the machine framework. The said stands or cheek-pieces are formed with guide-bearings 10^a, 11^a, Figs. 3 and 4, receiving the opposite end-portions of the said stud, and within which endwise movement of the stud for the purposes of the feed of the material operated upon takes place. This movement is communicated to the stud through the feed-lever 12, Figs. 1 and 4, which is regularly vibrated during the working of the machine.

The particular means for operating the feed-lever forms no portion of the invention herein claimed. Any preferred means may be employed in practice. One of the carriers, in this embodiment of the invention the needle-carrier, has an elongated or sleeve-like hub 6^d, Fig. 4, which surrounds a portion of the length of the supporting-stud 9. The said hub or sleeve is combined with the stud in a manner providing for free oscillatory turning movement of the carrier around the stud, as required for the entrance of the needle into the hole previously made by the awl in the material operated upon, and its withdrawal from such hole, but preventing relative movement between the carrier and stud in the direction of the length of the stud, so that the carrier is compelled to accompany the stud as the latter is moved endwise for the purposes of the feed. To this end, as one feature of the invention, the stud is furnished with cones 9^a, 9^b, the small ends of which face each other, and the hub or sleeve 6^d has tapering enlargements of its bore at the opposite ends thereof to receive and fit the said cones. The hub or sleeve is mounted upon

and between the cones. Preferably, the cone 9^a is fixed and integral with the stud, and provided by turning down the latter to form such cone, the remainder of the length of 5 the stud to one end of the latter being in addition turned down to form a cylindrical portion 9^c of reduced diameter; and the cone 9^b made in a separate piece and adjustably connected with the reduced portion 9^c of the stud beyond cone 9^a. The construction may vary in different cases. Herein, the cone 9^b is sleeve-like and fits upon the said reduced portion, and the exterior of the latter and interior of the said 15 cone are screw-threaded, so that the cone screws into place upon the stud.

For convenience in turning the cone 9^b in screwing it on or off, and in adjusting it, the outer end thereof is constructed properly to 20 be engaged by a suitable tool. In this instance it is slabbed off at two sides for the reception of a wrench or the like, as shown in Fig. 3. By adjustment of the cone 9^b a proper and snug fit of the hub 6^d upon the 25 two cones may be secured. To enable the adjustable cone to be locked in adjusted position, a hole is drilled lengthwise into the small end of the stud 9, and threaded, and the stem of a locking screw 13 is inserted 30 into such hole. This locking screw is turned in until its radially-projecting flange engages with the outer end of the adjustable cone.

The large end of supporting-stud 9 is of 35 a diameter which fills the guide-bearing 10^a of the stand 10, and such portion has a sliding fit in the said guide-bearing. The cone 9^b has a cylindrical portion of the same diameter as the hub or sleeve 6^d of the carrier 40 6, and such portion of the said cone, and a portion of the said hub or sleeve, occupy the guide-bearing 11^a in the stand 11 and have a sliding fit therein. The other carrier, i. e., the awl-carrier 7, is constructed with a 45 cylindrical hub 7^d, shorter than the sleeve or hub 6^d of the needle-carrier. The hub 7^d is sleeved upon the exterior of the said sleeve or hub 6^d. Thereby the awl-carrier is supported. As usual, the awl-carrier has 50 capacity for oscillating movement, as required for the entrance of the awl into the material operated upon to form a hole in such material for the admission of the needle, and its withdrawal from the hole thus formed. To 55 insure that the awl shall swing or turn always in the same plane, and prevent the awl-carrier and awl from participating in the feed-movements, a radial flange 7^e is provided upon the outer end of hub 7^d and 60 a two-part or split cap 14, 14, is detachably fastened to the stand or cheek-piece 11, the said cap having an inwardly facing lip or flange which overlaps the flange 7^e. This 65 cap is in two parts or split to enable its parts to be separated for the admission of the

flanged portion of the hub of the awl-carrier. When the parts have been brought into proper relations and closed together properly upon the flange-portion of the hub 7^d the latter and the awl-carrier and awl are 70 free to rock or swing but cannot move transversely.

Power is transmitted to the awl-carrier through connections between the main shaft 2 and the arm 15 extending from the awl-carrier, as presently will be explained, and movement is transmitted from the awl-carrier to the needle-carrier by means of a pin 16 carried by the needle-carrier, extending 75 therefrom parallel with the axis about which 80 the two carriers turn, and occupying a hole made transversely through the awl-carrier. The said pin is of a length exceeding that of the greatest extent of feed-movement, so that it always remains engaged with the awl-carrier, throughout the feed-movement of the needle-carrier and the recovery-stroke. As coupled together by means of pin 16 and 85 the hole it occupies in the awl-carrier, the awl-carrier and needle-carrier swing in unison 90 about their common center or axis of rotation, while the needle-carrier and needle are permitted the transverse feed-movements. In these feed-movements the sleeve or hub 6^d of the needle-carrier slides lengthwise within the hub 7^d of the awl-carrier. 95

It will be perceived that not only does the sleeve or hub 6^d of the needle-carrier constitute an internal support for the hub 7^d of the awl-carrier, but the two sleeves or hubs 100 bridged to reduced part of the stud 9 between the two cones 9^a, 9^b, thereby reinforcing the internal support for the two carriers.

The power connections through which motion is transmitted from the main shaft 2 to 105 the awl-carrier and needle-carrier, to oscillate the said carriers and the awl and needle carried thereby do not form any part of the invention. Those illustrated in the drawings, comprise a crank 17, Figs. 1 and 2, 110 fixedly connected with the said main shaft, a link 29 in pivotal engagement by one end thereof with the said crank, a rocker or walking-beam lever having a rearwardly-extending arm 30 with which the other end 115 of the said link is pivotally engaged and a forwardly-extending arm 31, and a link 32 having one end thereof pivotally engaged at 31^a with the said forwardly-extending arm 31 and the other end thereof pivotally engaged at 32^a with the arm 15 of the awl-carrier. 120

For the purposes of the needle-feed, the needle must be caused to remain in the material (work) at the time of the feed-movement. The devices which have last been described are contrived with especial reference to causing the needle to occupy its elevated position shown in Fig. 2, with its shank-portion in the hole in the material 125 130

operated upon, at the moment when the feed-movement begins, and to maintaining the needle in this elevated position to the full extent or limit of the movement by which the material is advanced for the purposes of the feed. Thereby the strain is applied to the shank-portion of the needle, and tendency to spring and bend or break the needle is obviated. In securing this action the parts are combined and arranged so that the center or point of pivotal connection 31^a between the forwardly-extending arm 31 of the rocker or walking-beam lever and the upper end of link 32 shall arrive close to, or at, or slightly past the line joining the center or point of connection 32^a between link 32 and arm 15 and the axis or center of movement 31^b of the said rocker or walking-beam lever. Thereby a dwell, or practically a dwell, of the needle in its highest position is secured with the advantage indicated above.

In machines of this class it is usual to provide for raising the presser-foot slightly at the moment of the feed, to release the material (work) to be fed. As a result of the dwell just described of the needle in its most highly elevated position it is rendered possible to cause the needle to assume and occupy its highest position during the lifting of the presser-foot. In the absence of the dwell, or if the lifting of the presser-foot should occur during any portion of the ascending movement of the needle, the continuance of such ascending movement would cause the needle to raise the work with it following the raising of the presser-foot.

The operative connection between the feed-lever 12 and the longitudinally-movable supporting-stud 9 of the needle-carrier, etc., may be variously established in practice. As one feature of the invention I employ in the illustrated embodiment of the general invention a collar 33 which surrounds and fits a cylindrical intermediate portion of the stud. This collar is split at one side, as at 33^a, Fig. 3, and provided with a screw 34 in connection with the two portions at the split, by means of which the collar may be tightened upon the stud so as to clamp it securely thereto. The collar is furnished at the rear with a short extension in which are formed, above and below, tapering holes to receive upper and lower cone-centers constituted by the tapering ends of screws 35, 35, carried by the forward end of feed-lever 12, as shown by dotted lines in Fig. 1. Thereby, through the movements which are communicated to the feed-lever for the purposes of the feed, and through the engagement of the said lever with the clamp, and through the fact that the clamp is clamped upon the stud 9, the said stud and the needle-carrier segment mounted thereon are compelled to move in unison

with the feed-lever. The clamp is held frictionally upon the exterior of the stud and the portion of the stud upon which the clamp is mounted is cylindrical, this construction permitting a shift or adjustment 70 of the clamp upon the stud with the utmost degree of nicety. This enables an adjustment to be made of the needle-carrier segment and needle with reference to the awl-carrier segment and awl so that at the starting end of the feed the center of the needle and the center of the awl may be brought into precisely the same plane, thereby insuring entire accuracy in the entrance of the needle into the hole previously punched 80 in the material by the awl.

I claim as my invention,

1. In a sewing machine, in combination, a curved needle, a curved awl, oscillating carriers for said needle and awl, one of said carriers having an elongated sleeve or hub, the other thereof having a hub which is sleeved upon the exterior of the said elongated sleeve or hub whereby one carrier is supported by the hub of the other, means 85 for holding the second carrier from transverse movement, and means for imparting a transverse reciprocatory movement to the carrier first mentioned.

2. In a sewing machine, in combination, a supporting-stud, a curved work-penetrating implement, a carrier therefor mounted on said stud with capacity to turn thereon, the said carrier and stud being held from independent movement lengthwise of the 100 stud, and a feed-lever connected with said stud by means of a friction-clamp engaging with an elongated cylindrical portion of the stud with capacity for adjustment of the stud lengthwise, whereby the plane of 105 action of said implement may be varied.

3. In a sewing machine, in combination, a supporting-stud having opposite cone-bearings, a curved work-penetrating implement, an oscillating carrier therefor having a sleeve or hub surrounding said stud and mounted upon and between the said cone-bearings, and a feed-lever adjustably connected with the said stud by means of a friction-clamp engaging with an elongated 110 cylindrical portion of the stud.

4. In a sewing machine, in combination, a carrier supporting-stud, a curved needle and a curved awl, oscillating carriers for said needle and awl, one of said carriers having a sleeve or hub surrounding the said stud and mounted thereon, and the other thereof having a hub which is sleeved upon the exterior of the said sleeve or hub.

5. In a sewing machine, in combination, a supporting stud, a curved needle, a curved awl, oscillating carriers for said needle and awl, one of said carriers having a sleeve or hub surrounding the said stud and mounted thereon, and the other thereof having a hub 120

- which is sleeved upon the exterior of the said sleeve or hub, means for actuating one of said carriers, and means for transmitting motion from such carrier to the other 5 thereof.
6. In a sewing machine, in combination, a carrier supporting stud, means for imparting feed-movements thereto, a curved needle, a curved awl, oscillating carriers for said 10 needle and awl, one of said carriers having an elongated sleeve or hub surrounding the said stud and mounted thereon with capacity to turn around the same but held from independent movement lengthwise of said 15 stud, the other of said carriers having a hub which is sleeved upon the exterior of the said elongated sleeve or hub, and means for holding the latter carrier from transverse movement.
- 20 7. In a sewing machine, in combination, a supporting-stud, means for imparting feed-movements thereto, a curved needle, a curved awl, oscillating carriers for said needle and awl, one of said carriers having an elongated sleeve or hub surrounding the 25 said stud and mounted thereon with capacity to turn around the same but held from independent movement lengthwise of the stud, the other carrier having a hub which is 30 sleeved upon the exterior of said elongated sleeve or hub, means for holding the latter carrier from partaking of the feed-movements, means for actuating one of said carriers, and means for transmitting motion 35 from such carrier to the other thereof.
8. In a sewing machine, in combination, a supporting-stud having cone-bearings, means for communicating feed-movements to said stud, a curved needle and a curved 40 awl, an oscillating carrier for one of the said implements having an elongated sleeve or hub surrounding said stud and mounted upon and between the said cone-bearings, an oscillating carrier for the other of said 45 implements having a hub which is sleeved upon the said elongated sleeve or hub, and means for holding the latter carrier from participation in the feed-movements.
9. In a sewing machine, in combination, 50 a supporting-stud having cone-bearings, means for communicating feed-movements to said stud, a curved needle and a curved awl, a carrier for one of said implements having an elongated sleeve or hub surrounding said stud and mounted upon and between the said cone-bearings, an oscillating carrier for the other of said implements having a hub which is sleeved upon the said elongated sleeve or hub, means for holding the latter carrier from participating in the feed-movements, means for actuating one of said carriers, and means for transmitting oscillatory motion from such carrier to the other. 55
10. In a sewing machine, in combination, a supporting-stud having cone-bearings, a curved needle, a curved awl, oscillating carriers for said implements, one thereof having a sleeve or hub mounted upon and between the said cone-bearings, means for imparting feed-movements to said stud, a guide-bearing for one portion of the stud, a guide-bearing in which said sleeve or hub and one of the cone-bearings fit, the carrier for the other implement having a hub which fits upon the sleeve or hub of the first carrier, and means for holding the second carrier from participating in the feed-movements. 60 70 75
11. In a sewing machine, in combination, a supporting-stud having cone-bearings, a curved needle, a curved awl, carriers for said implements, one carrier having a sleeve or hub mounted upon and between the cone-bearings, means for imparting feed-movements to the stud, a guide-bearing for one portion of the stud, a guide-bearing in which said sleeve or hub and one of the cone-bearings fit, the carrier for the other implement having a hub which fits upon the sleeve or hub of the first carrier, means for holding the second carrier from participating in the feed-movements, means for communicating oscillatory movement to one of the carriers, and a pin carried by such carrier, engaging with the other carrier, and transmitting oscillating movement to the latter. 80 85 90 95

In testimony whereof I affix my signature in presence of two witnesses.
